UNITED STATES PATENT OFFICE

93,386

DESIGN FOR A COMBINED PICTURE DISPLAY AND COMPACT CASE

Mack M. Forman, Providence, R. I.

Application July 14, 1934, Serial No. 52,593

Term of patent 3½ years

To all whom it may concern:

Be it known that I, MACK M. FORMAN, a citizen of the United States of America, residing in Providence, county of Providence, State of Rhode Island, have invented a new, original, and ornamental Design for a Combined Picture Display and Compact Case, of which the following is a specification, reference being had to the accompanying drawing, forming a part thereof.

Figures 1, 2 and 3 are perspective views of different positions of the parts of a combined picture display and compact case, showing my new design.

I claim:

The ornamental design for a combined picture display and compact case, substantially as shown.

MACK M. FORMAN.
